GAME BOARD AND PLAYING PIECES
THEREFOR

Albert H. Wheeler, Worcester, Mass.

Application November 30, 1946, Serial No. 713,356

2 Claims. (Cl. 273—131)

1

This invention relates to a game to be played by moving differentiated pieces over a game-board which is subdivided to provide playing spaces.

It is the general object of my invention to provide a game of this type in which each set of differentiated pieces, if cumulatively assembled in a predetermined order, will then constitute a complete production unit, such as an automobile, an airplane, or a speedboat.

A further object is to provide a game-board having regular playing spaces and also having additional spaces in which the playing pieces may be stored and in which cumulative assembly of the pieces in a predetermined order may be accomplished.

My invention further relates to arrangements and combinations of parts which will be hereinafter described and more particularly pointed out in the appended claims.

A preferred form of the invention is shown in the drawings, in which

Fig. 1 is a plan view of my improved game-board with the playing pieces in starting position thereon; and

Fig. 2 is a perspective view of the production unit achieved by cumulative assembly of the differentiated playing pieces in predetermined order.

Referring to Fig. 1, my improved game-board comprises a playing field F having longitudinal and transverse rows of playing spaces 10, arranged similarly to a checkerboard but shown in the drawing as comprising six longitudinal rows and eight transverse rows. Each longitudinal row thus has eight playing spaces and each horizontal row has six spaces, so that the playing field comprises forty-eight regular playing spaces. Any reasonable size of field may be used, however, and the number of playing spaces may be varied either longitudinally or transversely as desired.

At the upper and lower edges of the playing field F, additional rows 11, 12, 13 and 14 of auxiliary spaces are shown. The spaces in the inner additional rows 12 and 13 are designed to receive the playing pieces of the two opponents before the start of the game. These spaces may be designated with the distinguishing numbers of the pieces as indicated.

Each set of playing pieces has a distinctive color. The playing pieces of each set should differ from each other in appearance, and are herein shown as comprising the chassis, engine, rear end, body and two sets of wheels of an automobile, which parts are numbered from 1 to 6

inclusive. When cumulatively assembled, they form a complete production unit.

The outer additional rows 11 and 14 of auxiliary spaces constitute "Assembly lines" and are used in assembling the production units, as will be hereinafter explained.

The rules for moving the pieces may be widely varied, but ordinarily each piece may move one space forward or rearward or one space to the right or to the left. Each piece may also jump an adjacent piece, provided it can land in a vacant playing space 10. If the piece which is jumped belongs to an opponent, said piece is returned to the opponent's starting line.

When any playing piece has completed its progress across the playing field to the last transverse row of regular playing spaces, it may then be removed and placed on the auxiliary space in the adjacent additional inner row 12 or 13 which is numbered to receive that particular piece.

After the chassis (part No. 1) has thus reached additional inner row 13, for illustration, it will be placed in the No. 1 space in the "Assembly line" outer row 14. As soon as the engine (part No. 2) reaches the No. 2 space in row 13, the chassis may be moved to space No. 2 in row 14 and the engine may be placed thereon. The chassis and engine may then be moved to space No. 3 in the "Assembly line" to receive the rear end (part No. 3) as soon as that part is available, after which the body (part No. 4) and wheels (parts Nos. 5 and 6) are added by successive assembly moves.

As soon as a production unit is completely assembled, it may be rolled off at the end of the "Assembly line" (row 11 or 14), thus winning the game if the move is completed ahead of corresponding assembly by the opposing player.

It will be understood that the rules of the game may be substantially varied, providing the feature of cumulative assembly of differentiated parts in a predetermined order to complete a production unit is retained. The game may also be adapted to be played by four players, playing either individually or as partners, by the addition of rows of auxiliary spaces at the right and left of the playing field F.

It will also be understood that the production unit may represent any desired object, provided it contains the requisite number of differentiated parts and can be cumulatively assembled in a predetermined order.

The inner additional rows 12 and 13 may be omitted, if desired, in which case the end rows

of spaces 10 may be used for starting and final positions.

Having thus described my invention and the advantages thereof, I do not wish to be limited to the details herein disclosed, otherwise than as set forth in the claims, but what I claim is:

1. A game comprising a game-board having a playing field subdivided in longitudinal and transverse rows of playing spaces and having an additional row of auxiliary spaces equal in number to the longitudinal rows and extending transversely across each end of said playing field, in combination with two playing sets each comprising a plurality of differentiated playing pieces equal in number to the number of longitudinal rows and to the number of spaces in each additional row and constituting a single production unit when assembled, the auxiliary spaces in each additional row bearing consecutive numbers from one end of the row to the other, and the separate pieces in the associated set of playing pieces bearing the same consecutive numbers and indicating the order in which the pieces should be assembled to form a production unit.

2. A game comprising a game-board having a playing field subdivided in longitudinal and transverse rows of playing spaces and having an additional row of auxiliary spaces equal in number to the longitudinal rows and extending transversely across each end of said playing field, in

combination with two playing sets each comprising a plurality of differentiated playing pieces equal in number to the number of longitudinal rows and to the number of spaces in each additional row and constituting a single production unit when assembled, the auxiliary spaces in each additional row bearing consecutive numbers from one end of the row to the other to denote progressive assembly, and means to identify certain differentiated playing pieces with certain associated numbered auxiliary spaces and to thereby indicate the order in which the pieces should be assembled to form a production unit.
